Primary Examiner — Katherine Glennon

(57) **CLAIM**

The ornamental design for a watch dial, as shown and described.

DESCRIPTION

The patent or application file contains at least one drawing executed in color. Copies of this patent or patent application publication with color drawing(s) will be provided by the Office upon request and payment of the necessary fee.

2. Watch dial

2.1 is a perspective view of a watch dial showing my new design;

2.2 is a back view thereof;

2.3 is a left view thereof;

2.4 is a right view thereof;

2.5 is a top view thereof;

2.6 is a bottom view thereof;

2.7 is a front view thereof, shown in a first position;

2.8 is a front view thereof, shown in a second position;

2.9 is a front view thereof, shown in a third position; and

2.10 is a front view thereof, shown in a fourth position.

1 Claim, 10 Drawing Sheets

(6 of 10 Drawing Sheet(s) Filed in Color)
